UNITED STATES PATENT OFFICE

152,333

DESIGN FOR A ROCKING CHAIR

Louise M. Jones Foulke, Brooklyn, N. Y.

Application May 23, 1947, Serial No. 139,237

Term of patent 14 years

(Cl. D15—6)

To all whom it may concern:

Be it known that I, Louise M. Jones Foulke, a citizen of the United States, residing at Brooklyn, in the county of Kings, in the State of New York, have invented a new, original, and ornamental Design for a Rocking Chair, of which the following is a specification, reference being had to the accompanying drawing, forming a part thereof.

The figure is a perspective view of a rocking chair, showing my new design.

I claim:

The ornamental design for a rocking chair, as shown.

LOUISE M. JONES FOULKE.
